UNITED STATES PATENT OFFICE.

LEWIS B. NORRIS, OF SAPULPA, OKLAHOMA, ASSIGNOR OF ONE-HALF TO OMAR E. ROSE, OF SAPULPA, OKLAHOMA.

GATE.

Application filed October 14, 1926. Serial No. 141,576.

My present invention pertains to gates such as generally used upon farms; and it has for its object to provide a peculiar and advantageous gate constructed with a view to being unlatched and opened by an automobile and also constructed and arranged when released from an automobile to gravitate to a closed position and automatically latch itself in such position.

Other objects and practical advantages of the invention will be fully understood from the following description and claims when the same are read in connection with the drawings, accompanying and forming part 15 of this specification, in which:

Figure 1 is a side elevation illustrative of the gate construction constituting the best practical embodiment of my invention of which I am aware, and showing the gate as latched in closed position.

Figure 2 is a top plan view of the same.

Figure 3 is an enlarged fragmentary perspective illustrative of a part of the unlatching mechanism of the gate.

Figure 4 is an enlarged fragmentary section taken on the plane indicated by the line 4-4 of Figure 1.

Similar numerals of reference designate corresponding parts in all of the views of the drawings.

The posts 1 and 2 of my novel gate structure are appropriately fixed in the ground and are spaced apart in the conventional manner. The post 1 is provided at its back 35 with a vertically disposed guide 3 for a weight 4, and said post 1 is also equipped with a sheave 5 in a bracket 6 fixed as at 7 to the post.

The gate of my improvement is designated 40 by 8, and said gate 8 is connected through the medium of a cable 9 passed over the sheave 5 with the weight 4, and hence the gravitational movement of the weight 4 will serve after the gate has been opened as hereinafter described to assist in the closing of the gate, i. e. the restoration of the gate to the position shown in Figure 1.

It will be noted by comparison of Figures 1 and 2 that the post 1 is equipped with a 45 bracket 10 in which is a sheave 11, and that the bracket 10 is provided with a projection 12, preferably one of the journals of the sheave 11, which is disposed and movable in a longitudinal slot 13 in a longitudinal

bracket 14 superposed upon and fixed to the 55 upper edge of the gate. It will be readily understood that incident to opening and closing movement of the gate 8 which is pivotally mounted at 15 in a bracket carried by the post 1, the bracket 14 will move with the 60 gate relative to the bracket 10.

A cable 16 is passed about the sheave 11 and is passed through guides 16 and 17 on the gate 8 and about the lower portion of an upright lever 19, pivoted at 20 to a 65 bracket on the outer end of the gate. The said lever 19 is adapted to swing in a vertical plane longitudinally of the gate 8 and in the same vertical plane as said gate 8.

The post 2 is provided with a keeper 21 70 preferably shaped as best shown in Figure 2, and designed to cooperate with the said lever 19. It will also be noted from Figures 1 and 4 that the lever 19 is tubular and a vertically movable bolt 22, connected at 23 75 to the lever 19 is movable vertically in the lever 19 and adapted to cooperate with a lower keeper 24, said keeper 24 being disposed between inclines 25 arranged adjacent to the ground and also adjacent to the post 80 2 and extending at opposite sides of the vertical plane of the gate 8 when said gate 8 is in closed position. A cable 22* is connected to the bolt 22, and is carried upwardly through the lever 19 and over a pulley 23* in the lever 19 and then through an opening 24* in the lever 19, and is connected to a bracket 50 fixed on the gate 8.

The gate 8 is provided at an intermediate 90 point in its length with an upright 30 having a portion 31 of circular cross section, and pivoted on the said portion 31 of the upright 30 are horizontally movable lever arms 32 which are connected together at their heel ends and are also connected 95 through the medium of a cross bar 33 which extends through the gate 8 as clearly shown in Figure 2. The said lever arms 32 are designed to be engaged and moved by an automobile moved toward the gate 8, and in this connection it will be understood that the cross bar 33 is connected to the lower arm of a lever 34 which is pivoted at 35 on a second upright 36 of the gate 8 and is adapted to swing in the direction of the thickness of the gate.

To facilitate attachment of woven wire to the gate from the lever 34 is disposed be-

tween the upright 36 and a frame bar 36* shaped as shown in Figure 1 to accommodate the working parts.

As will be understood by comparison of Figures 1 and 3, the upper arm of the lever 34 is connected at 37 to a lever plate 38 pivotally connected at 39 to the gate 8, and hence it will be understood that movement of the lever arms 32 will be attended by rocking 10 of the plate 38 about its axis.

The upright lever 19 is provided at opposite sides with eyes 40, Figures 1 and 2, and extending loosely through the said eyes 40 are longitudinal rods 41 with heads 42 at 15 their forward ends and also with pendent arms 43. The said rods 41 are pivotally connected at their rear ends to opposite side portions of the lever plate 38 as best shown in Figure 3.

20 The gate 8 is provided at the upper portion of its swinging end with a loop 50 which extends beyond the ends of the gate and loosely receives the upper portion of the lever 19, as shown in Figure 2.

25 Pivotedly connected at 51 to opposite sides of the forward portion of the gate 8 are angular levers 52, the upper arms of which are connected through links 53 with the arms 43 on the longitudinal rods 41. The 30 lower forwardly directed portions of the levers 52 are designed to cooperate with the keeper 21 in the manner hereinafter explicitly set forth.

In the practical operation of my novel 35 gate, it will be apparent that when an automobile approaching the gate abuts against and moves one of the arms 32, the lever 34 will be rocked and the upper portion of the lever 19 will be moved out of the keeper 21; also, the bolt 22 will be raised out of the keeper 24. At the same time the angular 40 levers 52 will be rocked, whereby said levers 52 acting against the keeper 21 will assist in the disengagement of lever 19 from the keeper 21. Thereupon continued movement 45 of the automobile against one of the arms 32 will move the gate to open position, and thereafter when the gate is released from the automobile the gravitation of the weight 50 4 will tend to return the gate to its closed position.

As the gate approaches its closed position, the lever 19 will snap into the keeper 21, and the bolt 22 will travel upwardly on one 55 of the inclines 25 and then will drop into the keeper 24 with the result that the gate will be securely though automatically latched in closed position.

It will be understood from the foregoing 60 that the kicking action of the levers 52 against the keeper 21 will operate to move the rear upper portion of the gate rearwardly, and that said movement of the gate will be with respect to the bracket 10, and that 65 when the gate approaches its closed position,

the rear upper portion of the gate will move forwardly with respect to the bracket 10 and will render the cable 16 taut.

It will be apparent from the foregoing 70 that my novel gate is simple and inexpensive in construction, notwithstanding the capacity of function ascribed to the gate, and that the gate is reliable in operation, and in general, is well adapted to withstand the usage to which farm gates are ordinarily 75 subjected.

I have entered into a detailed description 80 of the construction and relative arrangement of the parts embraced in the present and preferred embodiment of my invention in order to impart a full, clear, and exact understanding of the said embodiment. I do not desire, however, to be understood as limiting myself to the structure disclosed, my invention being defined by my appended 85 claims within the scope of which structural changes or modifications may be made without departure from my invention.

Having thus described the invention, what I claim is:—

1. In a gate, and in combination, a swinging gate, gravitational means for returning the gate to closed position subsequently to opening of the gate, a post opposed to the swinging end of the gate and having a keeper, a lever pivotally connected to the swinging end of the gate and rockable in the plane of the gate and in the direction of the length thereof, a bolt carried by the lower portion of said lever and connected to the gate, a keeper adjacent to said bolt, levers connected to the gate and adapted to exert a kicking action against the first named keeper to move said keeper, longitudinal rods carried by the gate and connected to the upright lever and also connected to said kicking levers, a loop on the gate and loosely receiving the upright lever, a swingable plate carried by the gate and connected to said longitudinal rods, an upright lever connected to the gate and connected to said swingable plate, and lever arms disposed at opposite sides of the gate and carried thereby and connected with the last named lever; said lever arms being adapted to be engaged and moved by an automobile approaching the sides of the gate.

2. In a gate and in combination, a post, a bracket thereon, a swingable gate having a pintle disposed in said bracket, a second bracket on said post, a sheave in the last named bracket, a member on the gate and engaged with and movable longitudinally relative to the last named bracket, a weight guide on the post, a cable guided on the post and interposed between and connected to the gate and a weight movable in said guide, an upright lever carried by the swinging end of the gate and having a vertically movable bolt, a connection between the gate and said 120 125 130

bolt, a cable guided about the said sheave and also guided about said upright lever, a latch post, a keeper adjacent the latch post to coact with said bolt, a keeper on said latch post to coact with said upright lever, and automobile controlled means on the gate for releasing the bolt and lever from their respective keepers.

3. In a gate and in combination, a swingable gate, a post adjacent to the swinging end of the gate, lower and upper keepers, an upright lever pivoted to the swinging end of the gate and arranged beyond said end and rockable in the direction of the length of the gate, said lever to cooperate with the upper keeper, means arranged in and movable relative to said lever to cooperate with the lower keeper, and automobile controlled means for disengaging said means and said upright lever from the lower and upper keepers; a hinge post the lower portion of the hinged end of the said gate being hinged to said hinge post, a bracket carried by said hinge post and equipped with a sheave, weight means associated with the gate and said hinge post for returning the gate to closed position, a member on the rear portion of the gate and movable with respect to said bracket, and a cable guided on the gate and passed about said sheave and connected to the upright lever.

4. In a gate and in combination, a swingable gate, a post adjacent to the swinging

end of the gate, lower and upper keepers, an upright lever pivoted to the swinging end of the gate and arranged beyond said end and rockable in the direction of the length of the gate, said lever to co-operate with the upper keeper and having a vertically movable bolt to cooperate with the lower keeper, and automobile controlling means for disengaging said upright lever from the upper keeper and said bolt from the lower keeper.

5. In a gate and in combination, a swingable gate, a post adjacent to the swinging end of the gate, lower and upper keepers, an upright lever pivoted to the swinging end of the gate and arranged beyond said end and rockable in the direction of the length of the gate, said lever to cooperate with the upper keeper and having a vertically movable bolt to cooperate with the lower keeper, and automobile controlling means for disengaging said upright lever from the upper keeper and said bolt from the lower keeper; the said upright lever being provided with a vertical bore and a pulley at the upper end of said bore, the gate being provided with a forwardly projecting bracket at its forward end adjacent to its upper edge, and a cable being passed through said bore and over said pulley and interposed between and connected to the bolt and said bracket.

In testimony whereof I affix my signature.

LEWIS B. NORRIS.
